CLAIM

The ornamental design for a cradle or similar article, substantially as shown and described.

DESCRIPTION

FIG. 1 is a perspective view of a cradle or similar article showing my design;

FIG. 2 is a perspective view of a modified form thereof;

FIG. 3 is a top plan view;

FIG. 4 is a bottom plan view;

FIG. 5 is an elevational view showing one of the two identical sides;

FIG. 6 is an end view taken from the left in FIG. 1, the appearance of the right end being a mirror image thereof; and

FIG. 7 is an end view taken from the left in FIG. 2.

FIG 4
